OTHER PUBLICATIONS Wikipedia, List of Convex Uniform Tilings [online], retrieved from http://en.wikipedia.org/wiki/List_of_uniform_tilings posted at least as early as Oct. 12, 2005 [retrieved on Nov. 1, 2012].*Primary Examiner* — Karen S Acker(74) *Attorney, Agent, or Firm* — Laura L. Bozek(57) **CLAIM**

The ornamental design for a paper product, as shown and described.

DESCRIPTION

The sole FIGURE is a top plan view of a paper product illustrating the claimed design. The outer perimeter of broken lines defines the boundaries of the claimed design and forms no part thereof. Thickness forms no part of the claimed design.
